UNITED STATES PATENT OFFICE.

CHARLES A. CHASE AND NEWELL B. PARSONS, OF CHICAGO, ILLINOIS; SAID PARSONS
ASSIGNOR TO SAID CHASE.

ELECTRIC SIGN-BOARD.

1,258,872.

Specification of Letters Patent. Patented Mar. 12, 1918.

Application filed September 25, 1914. Serial No. 863,441.

To all whom it may concern:

Be it known that we, CHARLES A. CHASE and NEWELL B. PARSONS, citizens of the United States, residing at Chicago, in the county of Cook and State of Illinois, have invented certain new and useful Improvements in Electric Sign-Boards, of which the following is a specification.

Our invention relates more particularly to that class of sign boards in which the letters are removable at will and provided each with a series of lamps which, when the letter is in position on the sign board, are in circuit with a source of electrical energy.

10 It is the object of our invention to produce a sign-board of this character in which the letters may be removed, replaced and interchanged with a minimum of effort, which is not easily damaged and that will resist 15 wear and the weather without deterioration.

In a former Patent No. 835,848 granted to us November 13, 1906, we disclosed an electric signboard of the same general character in which the backing or board proper 25 is formed with one or more horizontal slots according to the number of rows of letters which it is desired to apply to the signboard, the slots being inclined from the front to the rear, and the letters used therewith being 30 formed or provided with tangs or tongues upon their rear faces inclined to the letters at the same angle at which the slot is inclined to the face of the board so that the tangs when inserted in the slot form a support for the letter. The tangs are hollow 35 and form passages for the electric conductors which convey the current to the lamps upon the letters. Our present invention may be considered in a sense as an improvement 40 upon the construction of our former patent, the improvement relating to the means for connecting the electric circuits of the letters with the conductors upon the signboard for supplying current. In the improved 45 construction the walls of the slot which receive the letter-supporting tangs are of insulating material and have partially embedded therein bus-bars by which current is supplied to the letters, the upper and 50 lower faces of the tangs being formed or provided with conducting bars for contact with said bus-bars and connected respectively to the ends of the light circuit of the letter. Thus the letter may be secured upon 55 the signboard and in electrical connection

therewith by simply inserting the tang of the letter in the slot at any point along its length. In the preferred form, the walls of the slot are lined with strips of insulating material properly spaced from each other 60 by spacing blocks arranged at suitable intervals. In the accompanying drawings we have shown and in the following specification described in detail two preferred forms of our invention. It is to be understood, 65 however, that the specific disclosure is for the purpose of exemplification only and that the scope of our invention is defined in the following claims in which we have endeavored to distinguish it from the prior art so 70 far as known to us without, however, relinquishing or abandoning any portion or feature thereof.

In the accompanying drawings, Figure 1 is a vertical section through a sign-board 75 embodying our invention; Fig. 2 is an elevation partly in section of a detail; Fig. 3 is a section similar to Fig. 1, but with a part to be referred to later, omitted; Fig. 4 is a section on line 4—4 of Fig. 3 with parts 80 shown in elevation, a part being removed for the sake of clearness; Fig. 5 a vertical section on a plane parallel to that of Figs. 1 and 3 on line 5—5 of Fig. 4; Fig. 6 a rear elevation of one of the spacing blocks; Fig. 85 7 a rear elevation of the lining strips assembled with the spacers between them; and Fig. 8 a section of a modified form.

In Figs. 1 and 3, the body of the backing or sign-board proper is shown at 8 and may 90 be of metal, wood or any other suitable material. The board is divided by a series of horizontal slots 9, corresponding in number to the lines of letters to be used, there being a single slot for each line of letters. 95 The slots are inclined downwardly from the front to the rear of the board and lined with bakelite or similar non-conducting material, a strip of such material lining the upper side of the slot being shown at 10 and a strip lining the lower side of the slot 100 being shown at 11. The lining strips with their conductors and spacing elements are preferably assembled as shown in Figs. 5 and 7 before being placed in the slots of the 105 signboard. In order to provide for the firm attachment of these strips to the board, strip 10 is provided with a flange 12 extending upward from the forward edge thereof and engaged by screw bolts 13 by which it 110

is secured to the backing. The lower strip is provided with a downwardly extending flange 14 by which it also may be secured to the face of the sign-board and these strips line the slots throughout their length from end to end of the sign-board. A letter 15 is shown as secured to the sign-board being provided for this purpose with a tang 16 which projects downwardly at an angle 5 from an attaching plate 17 which is secured by screws 18 to said letter. This attaching member may also be made of bakelite or similar non-conducting material and the terminals 19 and 20 of the wiring system of the letter extend through bosses 21 on the forward face of the plate or bracket 17 and are embedded in the opposite faces of the tang or tongue respectively, as at 22, 23, (see Fig. 1). In order to properly secure the conductors in 10 the faces of the tang or tongue and yet permit them to project to contact with the bus-bars to be presently described, they are embedded into the respective faces of the tang being preferably secured in their proper position during the molding of the insulating member.

The bus-bars 24, 25 are preferably formed of sections of suitable length arranged end to end in the upper and lower lining members 10, 11, respectively (see dotted lines, 30 Fig. 7), and like the contacting members on the tangs of the letters are preferably embedded into the surface of the insulating material. Each section is provided with a 35 separate conductor or connector by which it is maintained in electrical connection with the source of electrical energy. Preferably these connectors are embedded in the faces of spacing blocks 26 which are arranged at 40 suitable intervals along the slot to maintain the proper spacing of the walls thereof and preferably to cover the meeting ends of the sectional bus-bars. As shown in Fig. 5 the spacing blocks are secured in place by bolts 45 27 extending therethrough and through both of the insulating lining strips of the slot and screws 28 which screw into sockets 29 embedded in the insulating material of a spacing block. The screws are preferably arranged 50 to one side of the spacing block, as shown in Figs. 4 and 6 for insulation, and the other side is occupied by the conductors 30, 31, upon the upper and lower faces of the blocks respectively. These conductors are 55 embedded in the blocks a sufficient distance so that their faces are brought firmly into contact with the respective bus-bars 24, 25 and yet permit the faces of the spacing blocks to be brought into close contact with 60 the liners of the slot. The contacts are secured in position by screws 32, and by reference to Figs. 4 and 6 it will be seen that the upper contact member is shorter than the lower because of the arrangement of the 65 bus-bars (Fig. 3) which are not opposite

each other but arranged with the upper bar more remote from the face of the board than the lower so that the weight of the letter borne by the tang will force the contact on the tang into intimate contact with the respective bus-bars. The ends of the conductors 30, 31 may be brazed or otherwise suitably secured to wires leading to a source of electrical energy. Obviously but a single conductor need be applied to each of the 70 sections of the bus-bars so that there need be only one of the spacing blocks 26 to each pair of bus-bar sections. If further spacing is found desirable a plain block without conductors may be interposed intermediate each 75 pair of spacing blocks 26.

Obviously it is not essential that the slots and the tangs on the letters be rectilinear. We have shown in Fig. 8 a curved construction in which the upper lining strip 10^a and the lower lining strip 11^a are curved in the arc of a circle and the tank 16^a is correspondingly curved, the bus-bars 24^a and 25^a being located as shown. A drainage opening 42 may be employed to drain the connection of the lower conductor. This construction has the advantage that the bus-bar 25^a is fully protected from the elements, the rear end of the slot being closed as shown. 85

By our improved construction we have 90 provided an electric signboard in which the letters are very readily removed and replaced or adjusted longitudinally of the slot to the desired distance from the adjacent letters irrespective of the width thereof and 95 the contacts of the letter are firmly pressed against their respective bus-bars. At the same time the construction is such that there is no danger of the letter being accidentally displaced or disconnected from the board. 100 While we have referred to the letters as each having a series of lamps mounted thereon, obviously a single lamp could be mounted on the letter or the lamp itself directly attached to a suitable tang for use in connection with 105 the backboard, or translating devices other than lamps might be employed with our improved connection.

We claim:

1. In a device of the class described, a 115 support having a horizontal slot therein, the walls of which are inclined from front to rear of said support, lining strips of insulating material in said slot, a pair of bus-bars at the upper and lower sides of said slot 120 respectively, and an electric fixture having a connecting tang thereon, said tang adapted to enter the slot and having upper and lower contacts thereon to engage the respective bus-bars.

2. In a device of the class described, a support having a horizontal slot therein the walls of which are inclined from front to rear of said support, longitudinally extending bus-bars rigidly mounted in said slot 130

at the upper and lower sides thereof respectively; an electric fixture having a tang adapted to enter said slot and contacts rigidly mounted on opposite sides of said tang 5 to engage the respective bus-bars.

3. In a device of the class described, a support having a horizontal slot therein the walls of which are of insulating material, longitudinal bus-bars rigidly mounted in 10 the upper and lower walls respectively of the slot and projecting from the surfaces thereof, an electric fixture, a tang thereon adapted to enter said slot, electric contacts fixed in the upper and lower surfaces respectively of said tang and adapted to engage the respective bus-bars, the vertical 15 diameter of the tang being materially less than the minimum diameter of the slot, the fixture being so attached to the tang that 20 the weight thereof tends to force the outer end of the tang upward.

4. In a device of the class described, a support having a horizontal slot therein, bus-bars on opposite sides of said slot, an 25 electric fixture having a tang adapted to enter said slot, said tang comprising a body of insulating material and a pair of contact bars extending longitudinally of the tang on the upper and lower faces thereof respectively, and partially embedded in but 30 projecting beyond said faces.

5. In a device of the class described, a support having a horizontal slot therein, inclined from the front to the rear of the 35 support and the walls of which are of insulating material, bus-bars rigidly supported on the upper and lower walls of said slot respectively, an electric fixture having a tang thereon adapted to enter said slot, said 40 tang being composed of insulating material and having upper and lower contact strips embedded therein, rigidly connected thereto and adapted to engage the contacts in the wall of the slot.

45 6. In a device of the class described, a support having a horizontal slot therein, the walls of which slot are of insulating material, a pair of bus-bars arranged within said slot, an electric fixture, a connecting tang 50 on said fixture adapted to enter said slot and having upper and lower contacts adapted to engage the respective bus-bars, the weight of the fixture being so arranged with reference to said tang that when in position 55 it tends to force the contacts on the tang into closer contact with the respective bus-bars.

7. In a device of the class described, a support having a horizontal slot therein, 60 bus-bars arranged respectively on the upper and lower walls of said slot, that upon the upper wall being more remote from the face

of the support than that upon the lower wall; an electric fixture having a tang adapted and designed to enter said slot, said 65 tang having contacts upon the upper and lower faces respectively thereof, adapted to make contact with the respective bus-bars, the weight of the fixture being so attached to the tang as to tend to throw the free end 70 of the tang upward.

8. A backing having a horizontal slot therein, said slot being inclined from the face to the rear of said board, lining strips of insulating material in said slot, bus-bars 75 in said lining strips extending longitudinally of said slot and offset transversely of said slot with respect to each other, and a device having a series of electric lamps thereon, and a tang inclined substantially at 80 the angle of said slot and adapted to enter the latter, and contacts arranged on the tang for engagement with the bus-bars in the slot.

9. A backing having a slot extending 85 longitudinally thereof, bus-bars extending longitudinally of the slot, spacing blocks in said slot, contact members in the faces of said spacing blocks engaging the respective bus-bars and a device having a series 90 of electric lamps thereon and a tang adapted to enter said slot and contacts on said tang adapted to engage the bus-bars.

10. A backing having a horizontal slot therein, the walls of the slot being of insulating material, a pair of bus-bars arranged 95 respectively in the upper and lower walls of said slot, a letter adapted to be attached to said sign-board having a series of electric lamps thereon, a tang on the letter 100 adapted to enter said slot and support the device, conductors rigidly connected to said tang and arranged to make contact with the conductors in the slot, the diameter of the tang being materially less than the distance between the conductors on the walls 105 of the slot.

11. In a device of the class described, a support having a horizontal slot therein, the walls of the slot being of insulating material, bus-bars arranged respectively on the upper and lower walls of said slot, the bus-bar on the upper wall being more remote from the face of the support than the bus-bar on the lower wall, and an electric fixture having a connecting tang thereon, said tang adapted to enter the slot, and having upper and lower contacts thereon to engage the respective bus-bars. 110 115
